UNITED STATES PATENT OFFICE.

HOWELL D. PRATT, OF PHILADELPHIA, PENNSYLVANIA, ASSIGNOR TO LINK-BELT COMPANY, OF CHICAGO, ILLINOIS, A CORPORATION OF ILLINOIS.

MACHINE FOR CLEANING RAILROAD-BALLAST. **REISSUED**

1,272,849.

Specification of Letters Patent. Patented July 16, 1918.

Application filed November 13, 1917. Serial No. 201,769.

To all whom it may concern:

Be it known that I, HOWELL D. PRATT, a citizen of the United States, residing in Philadelphia, Pennsylvania, have invented 5 certain Improvements in Machines for Cleaning Railroad-Ballast, of which the following is a specification.

One object of my invention is to construct a machine for mechanically cleaning or 10 screening railway ballast.

A further object of the invention is to provide a machine which can be located between the two tracks of a railroad so as to remove and screen the ballast at the 15 point between the two tracks and also that raked into the space from between the ties.

A still further object of the invention is to design the machine so that the material 20 screened from the ballast can be readily removed and deposited outside of the limits of the track or into cars.

In the accompanying drawings:

Figure 1 is a longitudinal sectional view 25 through the roadbed showing my improved ballast cleaning machine in operation;

Fig. 2 is a plan view; and

Fig. 3 is a transverse sectional view through the roadbed, showing the front end of the machine.

30 Referring to the drawings, 1 is the ordinary stone ballast of a railway. 2 are the ties and 3 are the rails of the tracks. These tracks are spaced a given distance apart, leaving a clear space between the ends of 35 the ties, as shown, and this space is usually filled with stone ballast, as well as the space between the several ties of each track.

After the ballast has been placed in the spaces between the ties, it becomes filled 40 with dirt and cinders to such an extent that the stones do not bind properly, one against the other, and in order to remove this dirt and cinders it has been the common practice to use manually operated forks for lifting the ballast and for sifting the dirt and cinders from the stone. By the use of my 45 invention, the sifting by manual labor is entirely eliminated.

In the present instance, 4 are angle bars 50 which form the rails on which my improved apparatus is supported. These rails can be permanently attached to the ties or they can be made removable, as desired, and while I have shown angle bars the rails may be 55 made of wood, or other suitable material.

5 are flat wheels, in the present instance, which are mounted on axles 6, supporting the lower frame 7 of my improved machine. Supported on this lower frame is an upper frame 8 connected to the lower frame by 60 uprights 9 at the rear end and by diagonal members 10 at the forward end, in the present instance. The construction may vary with the type of machine. Mounted on the forward end of the frame are brackets 65 11, carrying a shaft 12 on which are the bearings 13 for the diagonal beams 14, which carry the bucket elevator. A cross angle-beam 14^a, in the present instance, is secured to the beams 14, and rests on the ends 70 of the frame 7 and limits the downward movement of the elevator.

Mounted on the shaft 12 is a sprocket wheel 15 around which passes a chain 16. This chain passes around a sprocket wheel 75 17 mounted on a shaft 18 carried by bearings 19 on the lower ends of the beams 14. Secured to the chain at intervals are buckets 20 for receiving the ballast, and at the outer edge of the buckets are fingers 21, 80 which readily pass under the ballast so as to loosen the stones, thus allowing them to pass freely into the buckets. The buckets discharge the stone, cinders, and other dirt, 85 onto a screen 22, arranged at an incline directly back of the bucket elevator, and this screen can be agitated in any suitable manner so as to separate the cinders from the stones of the ballast. The stones are discharged from the rear of the screen into the 90 trench formed by the machine, and the cinders, and other dirt, in the present instance, fall into a box 23, or other suitable receptacle, under the machine. In the present instance, the box is supported by stirrups 95 24, pivoted to the frame, so that when the box is filled the operator can detach the box by moving the stirrups from under the box. Access may be had to the box from the front end of the machine by raising 100 the elevator sufficiently and it may be held in its raised position by any suitable means.

The screen, in the present instance, consists of a fixed frame 25, in which the screen itself is movably mounted, and attached to this 105 screen are angle bars 26 in which are threaded studs 27 to limit the upward movement of said screen, caused by the release of the coiled springs 28 after being compressed by the cam wheels 31 mounted on the shaft 110

32. These springs are carried by brackets 29 hung from the side members of the frame 25 of the screen, and on the screen are rollers 30, two at each side, in the present instance, 5 which are located in the path of said cam wheel 31. These shafts are driven in unison by a drive chain 33, which passes around sprocket wheels on the said shafts, and one of these shafts is driven through a chain 10 34 from a transverse shaft 35 having a gear 36, which meshes with a pinion 37 on the shaft 38 of an electric motor 39, although it will be understood that any suitable motor may be used to drive the 15 mechanism. The elevator is driven through a chain 40, which passes around a sprocket wheel 41 on the shaft 35 and a sprocket wheel 42 on the shaft 12.

It will be understood, however, that while 20 I have shown in dotted lines one arrangement for driving the mechanism the mechanism may be driven in any suitable manner and by any suitable motor without departing 25 from the essential features of the invention.

25 The operation of the machine is as follows:

If it be desired to clean the ballast of a double track road, the rails 4 for the machine are located in position on the ties, as 30 shown. Then, a certain portion of the ballast is excavated and the machine is located in the excavated portion. The machine can be moved forward by hand, or it may be driven by power, if desired. The elevator 35 is driven from the motor 39, and the buckets dig into the ballast in front of the machine and carry the detached particles of the ballast over the head of the elevator and discharge them onto the screen, and, as the 40 screen is agitated, the material flows down on the screen and the fine dust and cinders are separated from the stone, falling onto the box, or other receptacle, 23, while the stones are discharged into the trench at the 45 rear of the machine.

This machine not only cleans the ballast in the space between the tracks, but also in the space between the ties of the two tracks, by an operator raking the ballast from the 50 space between the ties to a position in the

path of the elevators. This is comparatively easy, as there is no lifting, or sifting, of the ballast by hand. The clean ballast can be readily placed between the ties, as the machine is traveling forward.

55

By manufacturing the machine as above described, it can be built to be within the clear space between the cars on the two tracks, so that the machine need not be removed when trains are passing. This is 60 clearly illustrated in Fig. 3, which shows the cars in dotted lines.

I claim:

1. The combination in a machine for cleaning ballast, of a frame arranged to travel 65 in the clear space between the tracks of a double track railway; means on said frame for removing the ballast from the roadbed; means for screening the ballast and returning it to the roadbed, the entire mechanism 70 being located on the frame in such position that trains can pass on either track without interfering with the frame and the mechanism carried thereby.

2. The combination in a machine for 75 cleaning railroad ballast, of rails independent of the rails of the track and mounted on the projecting ends of the ties; a frame less in width than the space between the ties and having wheels arranged to travel on the 80 rails; means on the frame for removing the ballast from the roadbed; means for screening the ballast and returning it to the roadbed; and means, carried by the frame, for receiving the fine material removed from the 85 ballast, the frame and its mechanism being of such a width and height as to be within the clear space between the cars traveling on the two tracks.

3. The combination in a machine for 90 cleaning ballast, of two tracks arranged side by side; rails on the adjoining ends of the ties of each track; and a frame having wheels adapted to the rails and located in the clear space between the cars traveling 95 on the two tracks, said frame carrying means for cleaning the ballast between the tracks.

In witness whereof I affix my signature.

HOWELL D. PRATT.
